STEAM LOCOMOTIVE

Gustav Arent Silversparre, Narbeth, Pa., assignor
to The Pennsylvania Railroad Company, Philadelphia, Pa., a corporation of Pennsylvania

Application December 27, 1943, Serial No. 515,657

3 Claims. (Cl. 105—172)

This invention relates to steam locomotives of the type having rigid wheelbases as distinguished from articulated locomotives of the Mallett type.

In rigid wheelbase locomotives as ordinarily constructed power is transmitted to plural drivers on a rigid wheelbase from a single pair of cylinders at the front ends of the locomotives.

The chief aims of my invention are to increase the pulling capacity of rigid wheelbase locomotives through application of power to different sets of drivers at opposite sides thereof from additional cylinders, and to provide for the support of the additional cylinders in such manner as to allow close spacing of contiguous drivers of the different sets and thus keep the overall wheelbase dimension of the locomotives restricted to limits prescribed by standard track curvatures.

Other objects and attendant advantages will appear from the following description of the attached drawing, wherein

Fig. 1 is a side elevation of a steam locomotive embodying my invention; and wherein

Fig. 2 is a fragmentary horizontal detail sectional view drawn to a larger scale and taken as indicated by the angled arrows II—II in Fig. 1.

The steam locomotive illustrated in Fig. 1 for convenience of exemplification herein, has a boiler 5 which may be of any approved construction, and which is supported at its front end by a small four-wheeled swivel truck 6, and at its rear end by a small four-wheeled rigid truck 7. In the interval between the two trucks 6 and 7 the boiler 5 is supported in this instance by two groups 8, 9 of drivers, each consisting of two pairs of wheels 10, 11 and 12, 13 which have their axles journaled in fixed bearings provided by the side members of the rigid framework 15 of the locomotive. The forward pair of cylinders 16 serve, through suitable connecting rods (not shown) to actuate the drivers 10 and 11 and may be supported in the usual way directly over the forward swivel truck 6. The rear cylinders 17 are fixedly supported by the side members of the rigid frame 15, which, for that purpose are respectively provided with lateral projections such as the one shown at 18 in Fig. 2 extending outward between the contiguous wheels 11 and 12 of the two driver sets, said projections and cylinders being preferably integrally formed with

said frame. It is to be particularly noted from Fig. 2 that the longitudinal dimension of the projections 18 is made considerably less than the length of the cylinders 17 with resultant provision, between the frame sides and the opposite ends of said cylinders, of clearance spaces into which the peripheries of the contiguous drivers 11, 12 of the two sets 8, 9 extend. This construction thus permits much closer spacing of the drivers 11, 12 than would otherwise be possible to the advantage of minimizing the overall rigid wheelbase of the locomotive. At its forward end, each projection 18 is recessed as at 19 to receive the upper end of a brake shoe hanger 20 for the driver 11 at the corresponding side of the locomotive. The pivot pin 21 for the hanger 20 is inserted through registering bores 22 and 23 respectively in the frame projection 18 and in the wall of the cylinder 17. The construction of the cylinders 17 may otherwise be conventional and accordingly need not be described in detail herein.

Having thus described my invention, I claim:

1. A steam locomotive having two groups of driving wheels at each side thereof; a journal frame for the axles of the several drivers; and serially arranged front and rear cylinders for actuating the respective driver groups, each rear cylinder being supported outward of the frame by a lateral projection of which the longitudinal dimension is considerably less than the length of said rear cylinder, with resultant provision of relatively deep clearances for projection thereinto of the peripheries of the contiguous wheels of the two driver groups at the corresponding side of the locomotive.

2. A steam locomotive according to claim 1, in which the rear cylinder supporting projections have recesses for the reception and pivoting of the upper ends of brake shoe hangers for the aft wheels of the leading driver set.

3. A steam locomotive according to claim 1, in which the rear cylinders and the supporting projections are integrally formed with the frame; and in which said projections have recesses for the reception and pivoting of the upper ends of brake shoe hangers for the aft wheels of the leading driver set.

GUSTAV ARENT SILVERSPARRE,
